ATTORNEY

UNITED STATES PATENT OFFICE.

WILLIAM W. JONES, OF TOLEDO, OHIO.

EXCAVATOR.

Application filed February 9, 1922. Serial No. 535,356.

To all whom it may concern:

Be it known that I, WILLIAM W. JONES, a citizen of the United States of America, residing at Toledo, Lucas County, Ohio, have invented new and useful Excavators, of which the following is a specification.

This invention relates to excavating.

This invention has utility when incorporated for the removal of material from water, as in deepening trenches or digging canals, etc.

Referring to the drawings:

Fig. 1 is a side elevation, with parts broken away, of an embodiment of the invention for operation upon a float in a canal or ditch;

Fig. 2 is a plan view of the device of Fig. 1, parts being broken away;

Fig. 3 is a section on the line III—III, Fig. 1, on an enlarged scale, with the ground wheel turned at 90° from the showing in Fig. 1;

Fig. 4 is an enlarged plan view of control and operating devices on the forward arm, for the digger, conveyor carrier and the ground wheel;

Fig. 5 is a fragmentary plan view of features of the centering device for shifting the float or barge centrally of the canal being cut;

Fig. 6 is a section showing features of the centering as well as anchoring devices of Fig. 5; and

Fig. 7 is a partial end elevation of the control devices for shifting the delivery conveyor, which in operation may distribute the material excavated along the canal bank.

In the embodiment of the vehicle herein shown it is a float or main support having a circular platform 1. This platform 1 is carried upon two main scow or barge chamber carrying or providing members 2, 3. The member 2 has a forward chamber 4, central chamber 5 and a rear chamber 6.

The parallel and similar scow member 3 has a forward chamber 7, an intermediate chamber 8 and a rearward chamber 9. The chambers 4 and 7 are similar, as well as the chambers 6, 9, and these chambers are ones which may have the ballast therein to vary the submergence of the vessel or main support. To this end the power supply, say from the source of electrical energy from a power plant on a following barge or scow, may be supplied to switch-board 10, which is shown as provided with reversing switches 11, 12,

13, 14. Each one of these switches controls a motor 15 connected to a pump 16, one for each chamber 4, 6, 7, 9. Accordingly, water may be pumped into or out of any one of these chambers and thus vary the submergence of the vessel, as well as determine its leveling.

This switch-board 10 is shown as having a main switch 16' which may be thrown in, and thereafter if switch 17 is thrown, power supply is given to motor 18 which through sprocket chain gearing 20 may drive shaft 21 at a reduced speed. This main shaft 21 for general drive, is shown as provided with chain gearing 22 extending to drive parallel shaft 23. From operator's station adjacent the switch-board 10, there is a control lever 24 connected by link 25 to throw control reversing clutch 26. This clutch may be of a type as shown in Patent 1,001,615, Budde, Aug. 29, 1911, transmission gearing, which is of a general type of structure placed upon the market as The Carlyle Johnson Machine Company, Manchester, Conn., marine reverse gear. This reverse gear device 26 serves to connect the shaft 23 for driving speed reduction worm gear 27, shaft 28, (Figs. 2, 5, 6,) having thereon bevel gear 29 in mesh with bevel gear 30 on vertical shaft 31. This vertical shaft 31 carries gear 32 in mesh with rack bar 33 on transversely extending plunger 34. Simultaneously, this gear 32 engages rack 35 upon bar 36 parallel to the bar 34. These bars 34, 36, respectively carry shoes or extended push plates 37 on their outer ends so that in the simultaneous operative action of these bars 34, 36, against opposite banks of a canal or ditch, the vessel carrying the platform 1 is placed centrally on such ditch.

When the scow or barge has been placed in the central position, lever 38 at the operating station may be thrown to be effective through link 39, reversing clutch 40, similar to the clutch 26, for rendering effective the sprocket chain gear 41 from the shaft 21 driving shaft 42 and through speed reduction gearing 43 operates shaft 44 connected through sprocket chain gearing 45 to drive pinion 46 raising or lowering spud 48. In this instance, when the push bars 34, 36, have effected centering by opposite traveling against the banks of the stream, this spud or anchor 48 may be driven downward for a pivot central anchor in holding the main support in position in the canal

or stream. The hand lever 38 may be thrown off to leave this spud 48 in its anchored down position while the hand lever 24 from off position may be thrown to the reverse drive for drawing in the arms 34, 36, thereby leaving the scow or the main platform 1 free for swinging upon this anchoring spud 48.

With the platform 1 anchored centrally of the canal and at its desired level, it is in order next to determine the angular position of the platform 1 as to the canal. This platform 1 has a forwardly extending arm 49. It may be desirable to swing this arm to an angular position in the canal for locating a point of starting in swinging the platform into position or in such form as may be desired. Inasmuch as this arm carries the ground wheel it is desirable to determine the level of the position of this ground wheel as to the ground upon which it is to travel. To this end at the main operating station is control lever 50 connected by link 51 to reverse gearing clutch 52 similar to reverse gear clutch 26. This reverse gear clutch 52 is effective for transmitting power from the shaft 21 which is connected by sprocket chain gearing 53 to shaft 54. From this shaft 54 drive, a bevel gear 55 connects bevel gear 56 on transverse shaft 57 as to the arm 49. This arm 49, (Fig. 2) in its extent forwardly of the platform 1 carries the mechanism for the control of the ground wheel. This shaft 57 on this forwardly extending arm 49 has worm wheel adjustment 58 for operating screw 59, and likewise similar worm wheel adjustment 60 for operating screw 61. These screws 59, 61, serve to reciprocate cross bracket 62 having central bearing 63 carrying yoke 64 for ground wheel 65. Accordingly, as this yoke 62 is elevated the ground wheel 65 is lifted off the ground for leveling the float or platform 1, while upon reverse throwing of this control lever 50 the ground wheel 65 may be thrust downward to ground engaging position.

To effect directing of the ground wheel 65 in the desired direction, a power drive is provided. From the main operator's station adjacent the switch-board 10 the operator may throw reversing switch 66 and thereby energize motor 67 connected through speed reduction gearing 68 to drive shaft 69. The operator at said main station may then throw lever 70 effective through link 71, angle lever 72, link 73 and lever 74 for throwing clutch 75, (Figs. 2, 3, 4,) and thereby connect sprocket gearing 76 to drive shaft 77 carried by the crosshead 62 parallel with the shaft 57. This shaft 77 carries worm 78 in mesh with worm wheel 79 fast with the bearing 63 on the yoke 64 of the ground wheel 65. Accordingly, this ground wheel with its yoke 64 may be shifted into

any angular position as to the forwardly projecting arm 49 by the operation of the motor 67 in one direction or the other as determined by the switch 66 and as thrown in by the clutch 75 from the hand lever 70 at 70 the main driving station.

When the direction or this top range position is determined for this ground wheel 65 the hand lever 70 may be given a throw for shifting the clutch 75 from neutral position away from the driving of the yoke 64 into position effective for connecting the shaft 69 through gearing 80 to drive shaft 81 parallel with the shaft 57. This shaft 81 carried by the yoke 62 has bevel pinion 82 in mesh with bevel pinion 83 on vertical stem 84 (Fig. 3) centrally of the bearing 63. This stem 84 at its lower end carries bevel pinion 85 in mesh with bevel pinion 86 on shaft 87 transversely of the fork 64 carrying the ground wheel 65. This shaft 87 is effective through sprocket chain gearing 88 for positively driving the ground wheel 65. Accordingly, when it is desired to pull forward, if the ground wheel 65 be directed in line with the arm 49 it is effective. The switch 66 may be thrown out or else the lever 70 may be operated to disconnect the clutch 75 for driving. If the platform 1 is to be shifted angularly, then this ground wheel 65 would be directed to position transversely of this arm 49 and the platform 1 would be swung upon the spud or anchoring pin 48 as an axis.

With the main platform 1 thus properly located, it is now in order to direct the digger and elevator apparatus into position. To this end, at the main operator's station, control lever 89 may be shifted and thus through link 90 operate reversing gear and clutch 91 similar to the clutch reversing gear 26. There is thus connected through gearing 92 from the main shaft 21 a drive for the shaft 93 effective through worm gearing 94 for operating transverse shaft 95 extending across the opening between the main floats or pontoons 2, 3, in radial alignment with the arm 49. This shaft 95 has pinions 96 in mesh with racks 97 for operating main carrier 98 having sustaining wheels 99 operating on guide 100 for effecting travel of this main carrier 98 radially inward or outward as to the arm 49.

This shaft 95 also has therefrom sprocket gearing 101 to shaft 102 below the main platform 1. This shaft 102 has thereon pinions 103 in mesh with rack 104 effective for thrusting scoop 105 as the lower portion of the frame to a forward position, or upon reversal it may be retracted as may be found desirable. This reversal is effected by opposite throwing of lever 89 at the main operating station.

For determining the depth or position of the scoop 105 below the platform 1 of the

main support, reverse switch 106 at the main switch-board 10 adjacent the main operating station may be thrown for operating motor 107 upon carrier 98. This motor 107 is connected through sprocket chain reducing gearing 108 to drive shaft 109. This determination of the cutting depth for the operation of the excavator is usually one which is maintained once the structure is placed into use. Accordingly, instead of the control extending to the main operating station such control may be upon the carrier 98. To this end clutch arm 110 may be thrown for connecting the shaft 109 to sprocket chain gearing 111 for driving worm speed reduction 112 in operating shaft 113 transversely of the carrier or carriage 98 and parallel to the shaft 57. The transverse shaft 113 has pinions 114 in mesh with rack bars 115 downwardly extending between the scow sections 2, 3, in the arm 49 to connect to upstanding cheeks or shields 116 from the scoop 105.

For operation of the elevator from the scoop 105, 116, switch 117 at the main switch-board 10 may be thrown in to start motor 118 connected by speed reduction gearing 119 to drive shaft 120 over which extends endless apron 121 carrying flights 122. This endless apron 121 extends down about pulley 123 at the scoop 105, 116. Pivotally carried with this scoop 105, 116, at this shaft 123 is upwardly extending incline frame 124 mounting the motor 118 and the drive shaft 120 of this elevator conveyor 121, 122. This frame 124 has guide 125 in its sides coacting with guide shaft 126 carried by the upstanding brackets 127 from the deck 1 of this vessel or main support, whereby the travel of the carriage 98 radially in and out from the central position of this main platform 1, while maintaining the scoop 105 at a fixed trench depth position will care for the inclinations of this conveyor but still hold the conveyor or elevator in position to deliver to hopper 128.

The digger or actual slicing operation may be controlled from the main operating station after the feeding depth is determined for the scoop 105, 116, the clutch 110 may be thrown out and the clutch 129 thrown in. Accordingly, when from the main operating station the switch 106 is thrown the motor 107 is effective through gearing 108 clutch 129 and sprocket chain gearing 130 to drive through worm reduction gearing 131 transverse shaft 132 carrying pinions 133 in mesh with rack bars 134 downwardly extending to cutter or digger 135 operable as a slicer with its lower edge 136 entering the soil, which, as sliding upward therein may be urged outward by curved part 137 and held by cheek 138 to fall between the cheeks 116 of the scoop 105, to the slide 122 of the elevator. The main op-

erator may control the downward cutting of the slicer 135 by throwing in, out, and reversing the switch 106 without reshifting the clutch, which will lift the cutter for repetition of the operation. Before the operation is repeated, a desired forward pull of the platform 1 through the wheel 65, may be effected through the hand lever 70.

When the limit of forward cutting, as determined by the arm 49 is attained, the carriage 98 may be retracted or left at its forward position. Preferably it is retracted to get the slicer and scoop out of range and when so retracted the ground wheel 65 in the position shown in Fig. 1, may be driven to swing the platform 1 upon its pivot 48, a distance such that the cutter or digger 135 may widen the cut already made in a repetition of the steps forward continuing the digging or excavating operation.

The soil or material which is sliced down or cut by the digger 135, falls with a minimum of disturbance as to the surrounding water, between the shields 116 of the scoop 105, and so may be directly elevated out of the water with a minimum thereof being dissolved into the water or thrown into the stream. Accordingly, there is a reduced amount of silt and this mud is elevated by the flights 122 to fall into the hopper 128.

The excavated material as delivered into the hopper 128 may be continuously disposed of therefrom by delivery to a scow in the rear or upon a bank of the canal or ditch, or on either bank of the canal or ditch. The hopper 128 is mounted on a turn-table 139, from which extends a radial arm 140, the outer or free end of which is carried by bracket 142 extending to roller 143 swingable or traveling upon track 144 on the main platform 1. Along the side of the arm 140 is a run-way or track 145 for an operator. An operator upon this track 145 may be in convenient position adjacent a switch-board 146 having main switch 147 which when thrown in may permit the operator to throw reversing switch 148 to start motor 149 connected by speed reduction gearing 150 for driving the wheel 143 in effecting swinging of the arm 140 in such direction as may be desired for travel on the track 144 about the turn-table 139. Inasmuch as the switch 148 is a reversing switch it will determine the direction of travel of the wheel 143 in swinging the arm toward a bank or as to position as desired in the swinging of the platform 1, even for loading a following barge or for rear fill.

With the position of the arm 140 determined, the conveyor for removing material from the hopper 128 may be thrown into operation. To this end, switch 151 on the switch-board 146 may be thrown for starting motor 152 connected through speed re-

ducing gearing 153, 154, for driving shaft 155 over which extends endless conveyor belt 156 carried by the arm 140. The idle or inward end of this conveyor 156 is about 5 guide shaft 157 mounted in the turn-table end of the frame or arm 140.

The operator upon the track 145 may care for avoidance of any clogging in the hopper 128 as well as determine the position of this 10 arm 145 in giving proper distribution of material upon the bank at different angular shiftings of the main support or platform 1, not only for distribution along one bank, but as to along either bank.

15 The disclosure as herein has special value for operating in alluvial soil, more particularly in the region of the delta of the Mississippi, wherein the top soil is very loose and porous with a sub-soil which is more firm.

20 The great difficulty in such soil is that there may be agitation and disturbance of the loose soil for it to run freely back into the ditch or trench as cut, thereby filling in such trench and defeating the entire end for the 25 irrigation process. The machine as herein disclosed is one which will handle such loose soil and take it out of the ditch, trench, or canal, and in practice, the canal depth may be determined actually by the amount of soil 30 to be removed, and such soil actually removed by the digger, elevator and conveyor apparatus as herein disclosed.

By adjusting the position of the elevator the inclination of the digger may be determined and therefore 35 by the angle of repose for the bank may be such as one not readily to be disturbed, but to be maintained in practice against erosion.

If it be desired to provide a canal which 40 will retain water by a sort of levee at the bank, the porous superficial soil may be removed and the subsoil placed on the bank as a water tight levee. Whether or not the banks of the cut have a key therein to receive an impervious deposit to prevent 45 surface seepage, the material as removed may pack down for forming a tight bank or levee, which will require little if any treatment to give it a smooth finished form for a covering of grass to render it more substantial 50 against erosion.

There is not a tendency to produce large hardened or compressed clods or chunks. The cutting from the top down does not compress or disturb the soil removed, but 55 merely severs it from its position in the surrounding soil. The thickness of the cuts for each slice may be varied or be constant. The material as rolling toward the boat from the slicer to fall between the flights down upon 60 the elevator has a minimum tendency to roll the water, and due to the continuous travel of the elevator, at once it falls there toward, is picked up with no tendency to macerate but to be elevated in practically the same 65 shaving or block size as sliced off. The de-

posit from this first conveyor or elevator into the hopper is not one tending to break these fragments, and the second conveyor, in receiving these shaved masses, may deliver such directly upon the bank or levee, to have 70 such fall into compact relation with each other, thereby having a minimum of voids for any seepage therethrough. This material being uncompressed and in practically the same condition as to the fragments as such material of the fragments had before removed, there is present all the elements for homogenous bank or levee production.

The method herein disclosed for removing the soil by cutting down has considerable 80 advantage as to the sides of the ditch or canal, in that the original stratification at such cut is not disturbed. The digger in working down merely shaves off the section of soil. In the particular instance as heretofore disclosed, wherein the top soil is quite friable and porous, with a more compact but readily removable subsoil, the cutter may pass directly through the loose material 85 without fracturing such material as to sub-layer and then proceed on down to the required depth in the sub-layer of layers. This preservation of the strata line at the 90 ditch or canal banks is a material factor against bank slope disintegration. 95

As to the vehicle or pontoon vessel proper as herein disclosed, there may be operation with practical elimination of boat lunges to disturb the bank. One factor in this steady- 100 ing is the ground wheel. Another important factor in this steadyng is that the working load is disposed so centrally of the vessel that even when working along one bank of the canal instead of straight ahead, there is not a tendency to rock the craft. The vessel 105 lines up with its working direction at all times as to the cutting or digging. The two elevators operate continuously so there is not accumulation of load only so far as the digger operates intermittently. The digger 110 operation is not one tending to depress the vessel at the digging point but any tendency would be one to lift. However, the working arm has considerable weight acting as a lever forwardly thereof which within preferred ranges of operation, should absolutely 115 neutralize unbalancing tendency which might agitate the water about the vessel. The speed of operation as well as the rate thereof, not only as to thickness of slicing 120 but the rapidity with which such occur, may have the wide range of variation according to the soil as well as the capacity or power of the equipment hereunder as to the particular embodiment or installation. 125

What is claimed and it is desired to secure by United States Letters Patent is:

1. A support, an endless conveyor provided with flights, a frame for the conveyor carried by the support and projecting there- 130

below into position for working, and shield providing means for holding the frame downward away from the support and into the position for working.

5 2. A support, an endless conveyor provided with flights, a frame for the conveyor carried by the support and projecting therebelow, and shield providing actuating means for shifting the frame as to the support, said 70 actuating means including a movable rack bar between the frame and the support.

10 3. A support, an endless conveyor provided with flights, a frame for the conveyor carried by the support and projecting below the support, a scoop carried by the frame at the lower extremity thereof, and shield providing thrusting actuating means engaging the frame adjacent the scoop for forcing and holding the conveyor, frame, and scoop 75 away from the support.

15 4. A float support, an endless conveyor provided with flights, a frame for the conveyor carried by the support and projecting therebelow into position for working, and power means for varying the submergence of the support including a shield extending below the support and having hinge engagement with said conveyor.

20 5. A support, a first endless conveyor provided with flights, a frame for the conveyor carried by the support and projecting therebelow into position for working, a second conveyor to which the first conveyor may deliver, means for swinging the second conveyor as to the first conveyor, a digger, and a shield between the digger and the first conveyor for receiving directly all diggings from the digger, said shield being connected to the first conveyor and adjustable for determining the position of the first conveyor 25 as to the support.

25 6. A support, a holder for the support, an endless conveyor provided with flights, a frame for the conveyor carried by the support and projecting therebelow into position for working, means for angularly shifting on a vertical axis the support as to the holder for widening the effective position for working, and a slicing device for loosening and directing material to the conveyor.

30 7. A float support, pivotal anchoring means therefor, a conveyor provided with flights, a frame for the conveyor carried by the support, and projecting therebelow to a position for working, and means for swinging the support on its pivotal anchoring means as a vertical axis in effecting a swath range for the conveyor.

35 8. A float support, a locating means for the support, pivotal anchoring means for holding the support located, a conveyor provided with flights, a frame for the conveyor carried by the support and projecting therebelow to a position for working, and means 40 for swinging the support on its pivotal an-

choring means as a vertical axis for effecting a swath range for the conveyor.

9. A support, an endless conveyor provided with flights, a frame for the conveyor carried by the support and projecting therebelow into position for working, and means for adjusting the conveyor as to the support while maintaining the range of projection therebelow, said means including a rack bar and shield pivotally connected to the frame 70 remote from the support and a pinion for shifting said bar.

10. An excavator embodying a float support, a digger carrying arm, and a support shifting ground wheel carried by the arm. 80

11. An excavator embodying a float support, means anchoring the support for swinging, a digger carrying arm, and a ground wheel for swinging the support on a vertical axis. 85

12. An excavator embodying a float support, means anchoring the support for swinging on a vertical axis, release means for the anchoring means, a digger carrying arm, and a ground wheel for swinging the support on said vertical axis. 90

13. An excavator embodying a main support, an elevating conveyor, a frame for the conveyor, a hopper to which the conveyor delivers on a vertical axis, a holder for the support permitting swinging of the conveyor relatively thereto, and means for adjusting the conveyor toward and from the hopper in addition to said swinging. 95

14. An excavator embodying a main support, a first conveyor, a frame for the first conveyor, a hopper to which the first conveyor delivers, means for adjusting the first conveyor toward and from the hopper, a second conveyor to which the hopper delivers, a digger, and a shield having cheeks extending between the digger and the first conveyor for directing all of the diggings into the first conveyor, said cheeks being pivotally connected to said first conveyor. 100

15. An excavator embodying a main support, a first conveyor, a frame for the first conveyor, a hopper to which the first conveyor delivers, means for adjusting the first conveyor toward and from the hopper, a second conveyor to which the hopper delivers, and means for swinging the second conveyor with the hopper relatively to the first conveyor on a vertical axis. 105

16. A float carried excavator, a slicer digger carried thereby, a shield extending from the digger for holding the diggings, and an elevator for the diggings to which elevator the shield is pivotally connected. 110

17. A float carried excavator, a slicer digger carried thereby, an elevator for removing sliced material, and a shield extending from the digger to the elevator for holding diggings from dispersal, said shield being movable relatively to the elevator. 115

18. A float carried excavator, a slicer digger carried thereby, an elevator for removing sliced material, a continuous drive for the elevator, and a shield extending from the 5 digger to the elevator for holding diggings from dispersal, said shield being movable relatively to the elevator.
19. An excavator embodying a float, a slicer digger carried by the float, an elevator 10 carried by the float for removing sliced material, means for shifting the digger and elevator relatively angularly as to the float, and a shield extending from the digger to the elevator for holding diggings from dispersal, said shield being movable relatively 15 to the elevator.
20. An excavator embodying a main support, a pair of overhanging relatively angularly extending arms carried thereby, a conveyor 20 carried by one of the arms, and means for horizontally swinging one of said arms as to the other on a vertical axis.
21. An excavator embodying a main support, a pair of overhanging relatively angularly radially extending arms carried thereby, conveyors carried by the arms, and means 25 for swinging each of the arms as to the support, one of said conveyors embodying a frame shiftable along its arm, said swinging 30 of the arms being on a vertical axis.
22. An excavator embodying a main support, an overhanging radial arm providing a guide, a digger carried by said guide, and a shield carried by the guide and as to which shield the digger is movable, and an 35 elevator as to which the shield is movable in adjusting said elevator.
23. An excavator embodying a main support, holding means therefor, an overhanging radial arm providing a guide, a digger 40 carried by said guide, a conveyor carried by the arm, a frame for the conveyor, means for shifting the conveyor as to the arm and additional means for swinging the conveyor as to the holding means on a vertical axis. 45
24. An excavator embodying a main support, an overhanging arm radially extending from the support, an arc guide on the support for the arm, a conveyor carried by the arm, and means for actuating the arm to 50 travel on said guide in directing the conveyor for swinging on a vertical axis.
25. An excavator embodying a main support, support shifting and anchoring means, digging means, power mechanism, and a single operator's station for controlling the mechanism in operating said different means. 55

In witness whereof I affix my signature.
WILLIAM W. JONES.
